Salathiel Ellis of Mantorville, Minnesota.

Letters Patent No. 1653, dated Aug. 26, 1862.

The schedule referred to in these Letters Patent and making part of the same.

To all whom it may concern:

Be it known that I, Salathiel Ellis of the town of Mantorville, in the State of Minnesota, have invented or produced a new and original Design for a Composition in Bass or Silver, and do hereby declare that the following is a full and exact description of the same, reference being had to the accompanying photographic print.

The thing designed or produced in bass or silver is a medallion likeness of the head or bust of Abraham Lincoln, present President of the United States, and the same is fully represented in the drawing annexed.

Having thus described my invention, what I claim as new and desire to have secured to me by Letters Patent, is the design for a medallion likeness as above described and represented in the accompanying print.
